MAGNETOSTRICTIVE ELECTROACOUSTIC TRANSDUCER

Alexander Murdoch, Jr., Philadelphia, Pa., assignor to Radio Corporation of America, a corporation of Delaware

Application January 3, 1940, Serial No. 312,297

9 Claims. (Cl. 177—386)

1

This invention relates to magnetostrictive electroacoustic transducers and more especially to a magnetostrictively driven transducer for underwater signalling.

It is well known that electroacoustic transducers may be driven by magnetostrictive forces and that such devices may be used for underwater signalling. It is also known that, if a transducer having a diaphragm large compared to the operating wave length is driven as a whole, a sharply defined beam may be radiated. While the usefulness of a large diaphragm driven as a whole has been recognized, the result is difficult to obtain in practice. Furthermore, when a plurality of magnetostrictive elements are used to drive the diaphragm, various phasing problems arise.

It is one of the objects of this invention to provide an improved magnetostrictive electroacoustic transducer. Another object is to provide means for driving a large diaphragm at high efficiency by a plurality of properly spaced and phased magnetostrictive elements. Another object is to provide an efficient electroacoustic transducer for generating a sharply defined compressional wave in water. An additional object is to provide the optimum geometrical arrangement of a plurality of magnetostrictive elements for driving a diaphragm or to be driven thereby.

The invention will be described by referring to the accompanying drawing in which Fig. 1 is a sectional view of one embodiment of the invention; Figure 2 is a plan view of the diaphragm and magnetostrictive element arrangement; Figure 3 is a graphic illustration used in describing the invention; and Figure 4 is a wiring diagram of one arrangement of operating coils and polarizing means therefor.

Referring to Fig. 1, the electroacoustic transducer is included within a spherical housing of three parts: the front part 1, central part 3 and rear part 6. The three parts are separated by rubber gaskets 7. The front part 1 and the central part 3 are clamped together by circumferentially distributed cap screws 8. The gasket 7 between the front and central parts of the housing includes an annular recess 11 within which is clamped a heavy diaphragm 13. The diaphragm 13 has one or more recessed portions 15 adjacent the circumference. The recessed portions and the rubber gasket provide flexibility for the diaphragm mounting. The space between the diaphragm 13 and the front part 1 is filled with a liquid to increase the forward radiation of the device.

2

The rear part of the housing is secured to the central part by means of an arcuate member 17 which is fastened to the rear part by a cap screw 19 and to the central part by welding the ends 21 of the arcuate member thereto. The arcuate member 17 may be reinforced by a rib 23. The central part includes a back plate 25. The portion of the back plate next to the rear part of the housing includes a small air chamber 27 and a light weight diaphragm 29. The space between the diaphragm 29 and the rear part 6 of the housing forms an air chamber to reduce radiation toward the rear. The central part of the housing also includes a shoulder 31 upon which is mounted an insulated supporting member 33. A plurality of coils 35 are suitably mounted on the supporting member. Each of the coils is coaxially arranged with respect to the magnetostrictive elements 37 as hereinafter described.

20 A plurality of magnetostrictive elements 37 are fastened to the rear portion of the diaphragm 13 by welding, soldering, brazing, or the like 38. The elements are preferably nickel-steel tubes of an effective length equal to a quarter of the length of the wave to be radiated. The lower portion of each of the elements is slotted adjacent the actuating and magnetizing coils 35 to reduce losses therein. The free ends of the elements 37 are spaced from the back plate 25 to permit free

30 movement upon application of the driving forces. The tubular elements transfer the magnetostrictive forces to the diaphragm which, due to its large mass and to the impedance of the sound medium, moves through very short distances.

35 In order that the diaphragm move as a whole, it is desirable that the driving forces be suitably applied to the diaphragm at many points. It is also desirable to apply the forces efficiently. If the elements are arranged in groups forming

40 equilateral triangles, with common sides, it has been found that the forces are applied with maximum efficiency. The plurality of triangles are arranged as shown in Fig. 2. A single triangular arrangement of elements A, B and C is shown in

45 Fig. 3. If the broken line circles AA, BB and CC, which are tangent to each other, represent the spheres of influence or forces applied by or to the respective elements, it follows that less diaphragm area X is uninfluenced than by any other geometric arrangement of a plurality of diaphragm driving units. Furthermore, if other triangles are arranged common to each side of A, B, C, it follows that the added triangles are again the optimum geometric arrangement for applying 50 the magnetostrictive forces to the diaphragm.

The elements, under the influence of magnetostrictive forces, move through distances which are large compared to the diaphragm movements. It, therefore, follows that the elements act as transformers of the applied force. If the power is to be applied without excessive losses, the walls of the tubular elements must be sufficiently thick to transfer the applied power, and sufficiently light to properly match the several impedances of the transformer and diaphragm. By way of example, 320 nickel-steel tubes, having a wall thickness of 0.20 inch, an external diameter of $\frac{3}{8}$ of an inch, and a length of $2\frac{1}{4}$ inches, have been used in a transducer operating in sea water at a wave length of approximately 6 inches.

The coils are energized by direct current, as from batteries 38, 39 and 40, to apply a magnetizing force to the magnetostrictive elements. The coils may be energized by alternating currents from a suitable source 41 representing the signals to be radiated, or, if received signals are impressed on the diaphragm, currents corresponding to the signals may be derived from the magneto forces applied to the coils. The several coils may be connected in series-parallel arrays, as shown in Figure 4, for example, and energized in such proportions through the use of the polarizing batteries 38, 39, 40 and signal attenuating resistors 42 and 43 of different magnitudes, for example, as will best drive the diaphragm as a whole.

Thus the invention has been described as an electroacoustic transducer in which the diaphragm is driven by a plurality of magnetostrictive elements. The elements are disposed geometrically to apply driving forces most efficiently. The device may be operated by reception, in which case the forces driving the diaphragm establish signal currents in the coils used to energize the elements.

I claim as my invention:

1. An electroacoustic transducer including a diaphragm, a plurality of magnetostrictive elements attached to said diaphragm so that the points of attachment form a plurality of equilateral triangles having a number of common sides, said elements being so distributed over said diaphragm that the spheres of influence of adjacent elements border each other, and means for energizing said elements.

2. An electroacoustic transducer including a diaphragm, a plurality of tubular magnetostrictive elements attached to said diaphragm so that their axes are normal to the surface of the diaphragm and so that the points of attachment form a plurality of equilateral triangles having a number of common sides, said elements being so distributed over said diaphragm that the spheres of influence of adjacent elements border each other, and coil means surrounding each of said elements for applying thereto magnetizing forces.

3. An electroacoustic transducer including a diaphragm, a plurality of magnetostrictive elements attached to said diaphragm so that the points of attachment form a plurality of equilateral triangles having a number of common sides, said elements being made of tubular material having a slot therein and being so distributed over said diaphragm that the spheres of influence of adjacent elements border each other, and a plurality of coils a separate one of which surrounds each of said elements, said coils being arranged to permit free movement of the elements under the influence of magnetostrictive forces.

4. An electroacoustic transducer including a hollow spherical housing having a central supporting part and semispherical front and rear parts mounted thereon; a heavy diaphragm flexibly peripherally mounted within said housing so as to make a water-tight closure and comprising the inner face of said front part; a plurality of magnetostrictive elements attached to said heavy diaphragm normal to its surface and lying within said central part; a back plate carried by said central part and constituting the boundary between said central part and said rear part, the free end of said elements lying adjacent the inner surface of said back plate; means establishing a plurality of separate air chambers located successively between said back plate and the rear part of said housing; an energizing coil in energy transfer relation with each of said elements; and a non-compressible liquid substantially filling said front part, whereby vibratory energy may be transmitted between the medium surrounding said housing and said heavy diaphragm through said non-compressible liquid, and the transmission of said energy through said rear part is effectively prevented.

5. A device of the character described in claim 4 in which said means establishing a plurality of separate air chambers comprises a lightweight diaphragm mounted in spaced parallel relation to the outer surface of said back plate and lying within said rear part, and an arcuate member mounted within said rear part in uniformly spaced relation to the inner surface thereof.

6. In an electroacoustical transducer, a housing part comprising a hollow member, a vibratory diaphragm wholly within and closing off a portion of the interior at one end of said member, a plate within said member and closing off a portion of the other end of said member, electro-mechanical conversion means within said member interposed between said diaphragm and said plate and coupled to said diaphragm either for actuating said diaphragm in response to electrical signal energy supplied thereto or adapted to be energized by said diaphragm upon vibration thereof, and a second diaphragm connected to said plate in spaced relation thereto and lying within the closed off portion at said other end of said member whereby to provide an air chamber therebetween.

7. In an electroacoustical transducer, a housing part comprising a hollow member, a vibratory diaphragm wholly within and closing off a portion of the interior of one end of said member, a plate within said member and closing off a portion of the other end of said member, electro-mechanical conversion means within said member interposed between said diaphragm and said plate, said conversion means including a plurality of magnetostrictive elements secured to said diaphragm either for actuating said diaphragm in response to electrical signal energy supplied thereto or adapted to be energized by said diaphragm upon vibration thereof, and a second diaphragm connected to said plate in spaced relation thereto and lying within the closed off portion at said other end of said member, whereby to provide an air chamber therebetween.

8. In an electroacoustical transducer of the magnetostrictive type, the combination of a vibratory diaphragm, a plurality of magnetostrictive elements distributed over the area of and attached to said diaphragm, and a plurality of coils a separate one of which surrounds each of said elements, each one of said coils being adapt-

ed to influence its associated element to actuate said diaphragm over substantially a predetermined circular area, and the points of attachment of said elements to said diaphragm being so spaced that the perimeters of said circular areas are tangent to each other.

9. In an electroacoustical transducer of the magnetostrictive type, the combination of a vibratory diaphragm, a plurality of magnetostrictive elements distributed over the area of and attached to said diaphragm, and a plurality of coils a separate one of which surrounds each of said elements, each one of said coils being adapted to influence its associated element to actuate said diaphragm over substantially a predetermined circular area, and the points of attachment of said elements to said diaphragm being so spaced that the perimeters of said circular areas are tangent to each other and lines joining adjacent ones of said points form equilateral tri-

angles of which adjacent triangles have common sides.
